UNITED STATES PATENT OFFICE

PETER E. GELDHOF, OF SYRACUSE, NEW YORK, ASSIGNOR TO SYRACUSE WASHING MACHINE CORPORATION, OF SYRACUSE, NEW YORK, A CORPORATION OF DELAWARE

MECHANICAL CLOTHES WASHER

Application filed February 11, 1928. Serial No. 253,693.

This invention relates to a mechanical clothes washer involving the use of separate vats, one for receiving the clothes to be washed and the other for receiving the previously washed clothes to be rinsed and dried together with a washing mechanism in the washer vat for washing the clothes and centrifugal drying mechanism in the other vat for expelling the moisture from the clothes.

The main object is to bring the drier vat within the radius of one side of the washer vat so that both vats may be enclosed in one and the same cylindrical casing.

One of the specific objects is to make one of the vats in the form of a crescent and to nest the other vat in the concave side of the first-named vat within the radius of the convex side of said first-named vat.

Other objects and uses relating to specific parts of the machine will be brought out in the following description.

In the drawings:

Figure 1 is a vertical sectional view, partly in elevation, of a combination mechanical clothes washer and drier embodying the various features of the invention, showing one of the legs having its lower end broken away.

Figure 2 is a horizontal sectional view through both of the vats and drier cage showing the washing mechanism in top plan.

Figure 3 is a horizontal sectional view taken in the plane of line 3-3, Figure 1, except that the motor and pump are shown in top plan.

Figure 4 is a vertical sectional view taken in the plane of line 4-4, Figure 3.

Figure 5 is an enlarged horizontal sectional view through a portion of the centrifugal drier cage just above the bottom showing more clearly the outlet passages between the corrugated portion and periphery of the bottom of the cage.

The frame for supporting the vats comprises a circular horizontal deck or platform —1— and a superposed horizontal annulus or ring band —2— in vertically spaced parallel relation to the platform —1— a distance corresponding approximately to the vertical height of the vats, said lower deck —1— and band —2— being secured by bolts —3— or

equivalent fastening means to a plurality of, in this instance three, upright supporting legs —4— which are arranged in uniformly spaced relation circumferentially as shown more clearly in Figure 2.

A crescent-shaped washer vat —5— and a cylindrical drier vat —6— are mounted side by side upon the lower deck or platform —1— to project upwardly therefrom approximately the same height and are secured to said platform by suitable clamps —7— and —8— having their clamping members engaging the lower and upper surfaces of the bottoms of their respective vats.

The washer vat —5— is arranged with its convex side facing outwardly and its concave side facing the drier vat —6—, the convex side being cylindrical and of approximately the same radius as the platform —1— so that when the washer vat is placed in operative position its outer convex side may be disposed in vertical alignment with the corresponding periphery of the lower deck or platform —1—.

The central portion of the inner concave side of the vat is also cylindrical and concentric with the axis of the drier vat —6— but of less radius than the outer convex side. The circumferential length of the washer vat is somewhat greater than half the circumferential length of the lower deck —1— but of considerably less length than the full circumference of said deck so that when placed in operative position upon the deck the central portion of the concave side will be positioned near the vertical axis of the deck leaving ample space for the reception of the drier vat —6— upon and within the periphery of the cylindrical deck.

The opposite circumferential ends or horns —5— of the crescent-shaped washer vat —5— are preferably convex or rounded with equal radii to merge with the corresponding ends of the convex and concave sides of the vat, as shown more clearly in Figure 2.

The cylindrical drier vat —6— is partially nested in the concave side of the washer vat concentric therewith and wholly within the periphery of the deck —1— and, therefore,

wholly within the radius of the convex side of the washer vat so that both vats may be inclosed in one and the same cylindrical casing as shown in Figure 2.

The upper ends of the vats —5— and —6— are preferably disposed in the same horizontal plane parallel with the lower deck for receiving and supporting an upper circular deck —9— of slightly greater diameter than the lower deck and which may be removed and replaced at will when desired.

This upper deck is provided with openings —10— and —11— registering with the upper ends of their respective vats —5— and —6—, said openings being normally closed by lids —12— and —13— which are also removable and replaceable at will to permit access to the interiors of the corresponding vats.

These openings —10— and —11— and their corresponding lids —12— and —13— conform to the cross sectional shape of their respective vats, the opening —10— and its lid —12— being crescent-shaped and of approximately the area of the interior of the vat —5— while the opening —11— and its corresponding lid —13— are circular and of approximately the diameter of the interior of the drier vat —6—. Both of the vats —5— and —6— are preferably inclosed within an external sheet metal casing composed of circumferentially extending segments —14— of equal circumferential length and extending from the lower deck —1— to and slightly above the lower edge of the ring —2— concentric with the axis of the decks —1— and —9— and ring —2— and preferably corrugated circumferentially for stiffening purposes.

These casing sections —14— are more or less resilient and tensioned so that their ends tend to spring outwardly, but the opposite ends of each segment are loosely inserted between the inner faces of the legs —4— and adjacent portions of the periphery of the vats —5— and —6— to assist in holding them in operative position.

The lower edges of the casing sections —14— are provided with inturned flanges —14'— interposed between the bottoms of the vats —5— and —6— and upper face of the deck —1— to further assist in holding the case sections against vertical or radial displacement.

For a similar purpose the upper edges of the case sections are interposed between the inner face of the ring —2— and adjacent portions of the peripheries of the vats —5— and —6—.

The major portions of the casing sections —14— between the deck —1— and ring —2— are held in spaced relation to the adjacent portions of the vats —5— and —6— to form an intervening air chamber for sound-deadening purposes and also serve as

a heat-insulator to retain the heat of the washing fluid within the vats.

When placing these sections in operative positions the upper ends thereof are inserted under the lower edge of the ring —2— and raised slightly a sufficient distance to permit their flanges —14'— to be inserted under the bottoms of the vats —5— and —6— as shown in Figure 1, these operations being reversed when removing the sections from the vats.

One part of the clamp —7— for securing the bottom of the vat —5— to the underlying portion of the deck —1— comprises a flange formed on the lower end of a post —15— which is secured to said deck by bolts —16— or equivalent fastening means, the portions of the post below the flange being reduced in diameter and extended through a registering opening in the deck as shown in Figure 1.

The post —15— is tubular or hollow from end to end for receiving a vertically movable plunger —17— and is provided at its upper end with a gland —18— to form a liquid-tight joint with the plunger —17—.

The washing mechanism within the vat —5— may be of any suitable construction mounted upon the upper end of the plunger —17— above the gland —18— for vertical reciprocatory movement with said plunger and comprises, in this instance, a head —19— having a plurality of, in this instance two, spirally shaped spring arms —20— projecting outwardly and downwardly therefrom and carrying at their lower ends inverted cups or dashers —21— for engagement with the clothes and for producing more or less suction and pressure thereon as they are reciprocated.

The head —19— may be adjusted vertically upon the upper end of the plunger and held in its adjusted position by any suitable locking means, not necessary to herein illustrate or describe.

The clamp comprises a flanged collar —22— having its flange secured by bolts —23— or equivalent fastening means to the underlying portion of the deck —1—.

A tubular post —24— is secured at its lower end within the collar —22— to extend upwardly therefrom into the vat —6— coaxial therewith for receiving and supporting an upwardly tapered rotary cage or basket —25— within and coaxial with the vat —6—.

The cage or basket —25— preferably comprises a circular bottom section 25' of cast metal and an imperforate frusto-conical section 25" of sheet metal having its lower end bolted or otherwise secured to the periphery of the bottom section and its remaining portion tapered upwardly therefrom and open at the top to receive the articles to be dried.

The bottom section 25' is provided with an upwardly projecting central hub 26 and an upturned marginal flange 26' for receiving

and reinforcing the lower end of the sheet metal section 25", said bottom section being also provided with a circumferential series of openings 26" adjacent the flange 26' for drainage purposes.

5 The hub 26 is journaled intermediate its ends at 28 upon the periphery of the post 24 and has its upper end extended over the top of said post and removably secured to the 10 upper end of a vertical shaft 27 which extends downwardly through and some distance below the post and has its lower end connected by a coupling 29 to a coaxial driving shaft 30, Fig. 1.

15 The sheet metal section 25" is corrugated circumferentially at 31 from its lower end upwardly the major portion of its height for reinforcing purposes and also to form with the periphery of the bottom section a 20 series of outlet passages 31' through which the water which is expelled by centrifugal force from the clothes in the rotating cage is allowed to escape into the vat 6.

That is, when the cage 25 with the wet 25 clothes therein is rotated at sufficient speed the water contained in said clothes will be expelled by centrifugal force against the downwardly diverging walls of the cage to be deflected downwardly thereby and thence 30 outwardly through the passages 31' into the interior of the vat 6 and withdrawn therefrom by drainage or by a suitable suction pump presently described. The power unit includes, in this instance, an electric motor 35 —32— having its case bolted or otherwise secured to the underside of the deck —1— and its armature shaft —33— extended horizontally beyond the transverse vertical planes of the washer plunger —17— and drier shaft 40 —27— and operatively connected to the rotary impeller of the suitable pump —34— in a manner somewhat similar to that shown in my pending application Serial No. 242,613, filed December 27, 1927.

45 The intermediate portion of the shaft —33— is journaled in a gear case section —35— and is provided with a pinion —36—, Figure 3, while the outer end of the shaft is journaled in the casing of the pump —34—.

50 The casing of the pump —34— is secured by bolts —37— or equivalent fastening means to an extension of the gear case section —35— to permit the pump to be removed and replaced without disturbing the 55 other parts of the machine.

The gear case section —35— is also bolted or otherwise removably secured to the gear case section for the power-transmitting mechanism hereinafter described and by re- 60 moving the bolts of the pump case —34—, gear case section —35— and motor case —32—, this entire unit may be removed from the machine without disturbing the gear case for the power transmitting mechanism.

65 The gear case —38— is composed of sec-

tions —39— and —40— bolted or otherwise removably secured end to end for receiving and supporting the mechanisms for transmitting motion from the motor shaft —33— to the washer and drier mechanisms.

70

A cap section —41— is secured to the outer end of the gear case section —39— to form therewith a closed chamber for receiving a straight line motion mechanism for operating the washing mechanism.

75

Another case section —42— is secured to the outer end of the case section —40— for receiving portions of the mechanism for transmitting motion from the motor shaft —33— to the centrifugal drying device.

80

For these latter purposes a pair of horizontal counter shafts —43— and —44— are journaled in suitable bearings in the gear case —38— and in substantially the same horizontal plane as and parallel with the 85 motor shaft —33— but in spaced relation to said motor shaft and to each other as shown more clearly in Figure 3.

The means for transmitting rectilinear motion from the rotary shaft —43— to the 90 plunger —17— is quite similar to that set forth in my pending application Serial No. 234,517, filed Nov. 19, 1927, in that it comprises a crank arm —45— secured to the shaft —43— and provided with an eccentric axially extending stud —46— upon which is journaled a pinion —47— meshing with a fixed internal gear ring —48— which, in turn, is secured within the gear case section —39— coaxial with the axis of the shaft 100 —43—.

The pinion —47— is of substantially the same pitch diameter as the radius of the pitch diameter of the gear ring —48— and is provided with a diametrically extending crank 105 arm —49— carrying an axially extending stud —50— having its axis coincident with the pitch circle of the pinion and, therefore, the same radial distance from the axis of the stud —46— as the axis of the shaft —43— 110 so that when the pinion —47— is rotated by its planetary motion around the stationary gear ring —48— the stud —50— will be moved rectilinearly and vertically in the vertical plane of the axis of the shaft —43—. 115

A yoke —51— is secured to the lower end of the plunger —17— and is journaled upon the stud —50— for transmitting rectilinear motion from said stud to the plunger or rather for reciprocating the plunger —17— axially and rectilinearly.

The means for transmitting rotary motion from the motor shaft —33— to the washer shaft —43— comprises a gear —52— meshing with the pinion —36— on the motor shaft —33— and secured to a coaxial pinion —53— which is loosely journaled upon the shaft —44—.

This pinion —53— meshes with a relatively larger gear —55— which is loosely jour-

125

130

naled upon the washer shaft —43—. The gear —55— is movable axially on the shaft —43— into and out of clutching engagement with a clutch member —56— which is secured to the shaft —43— by means of a key or pin —57— to rotate therewith.

Any suitable means may be employed for shifting the gear —55— into and out of engagement with the clutch member —56— for starting and stopping the rotation of the shaft —43— and washing mechanism actuated thereby.

Drier operating mechanism

15 The outer end of the shaft —44— is geared to the lower end of the drier shaft —30— by means of beveled gears —58— and upon this shaft —44— is splined a combined clutch and brake collar —59— having its inner end 20 provided with a clutch member —60— which is movable into and out of frictional engagement with a clutch surface —61— on the loose gear —52— for making and breaking connection therewith.

19 The collar —59— is also provided with a brake flange —62— in axially spaced relation to the clutch flange —60— for receiving between them an axially movable shifting member —63— similar to that set forth in my 30 pending application Serial No. 242,613, filed December 27, 1927.

The shifting member —63— constitutes a non-rotatable brake member adapted to co-operate with the brake surface —62— and 35 may be operated by any suitable means such as the shifting lever —54— similar to that shown in my pending application, last referred to.

40 A coiled spring —65— is interposed between the hub of the gear —58— on the shaft —44— and collar —59— for urging the collar and its brake member —60— into frictional engagement with the continuously rotating gear —52— for effecting the rotation 45 of the drier cage —25— through the medium of the gears —58—.

When it is desired to stop the rotation of the drier cage the shifting members —63— 50 may be moved axially against the brake flange —62— to withdraw the collar —59— from frictional engagement with the gear —52— against the action of the spring —65— and at the same time retarding the rotation 55 of the collar —59— and shaft —44— on which it is splined by reason of the engagement of the brake member —63— with the brake surface —62—.

The suction side of the pump —34— is connected to suitable drainage outlets —66— and —67— in the bottoms of the vats —5— and —6— respectively for withdrawing water and moisture therefrom while its pressure side may be connected to a delivery nozzle similar to that set forth in my pending 65

application last referred to for directing the discharge of the water to other receptacles.

Operation

The rotation of the motor shaft —33— will 70 maintain continuous operation of the pump and also continuous operation of the gears —52— and —55— and when it is desired to operate the washing mechanism it is simply necessary to shift the gear —55— axially into engagement with the clutch member —56— thereby effecting the rotation of the shaft —43— and washing mechanism driven thereby.

On the other hand, if it is desired to stop 80 the operation of the washing mechanism the clutch gear —55— may be moved out of engagement with the clutch member —56—.

When it is desired to operate the centrifugal drier cage —25— the collar —59— may 85 be released to allow its spring —65— to force the clutch member —60— into engagement with the gear —52— thereby effecting the rotation of the cage —55— through the medium of the gears —58—.

On the other hand, when it is desired to stop the rotation of the basket —25— the collar —59— may be shifted axially by means of the shifting member —63— to withdraw the clutch member —60— from engagement 95 with the gear —52— and at the same time causing said shifting member to frictionally engage the brake surface —62— to retard and stop the rotation of the shaft —44— and drier mechanism driven thereby.

100 It will be noted that the vertical height of the cage or basket —31— is somewhat greater than the vertical movement or stroke of the cup-shaped dashers —21— and, therefore, of greater height than the clothes and washing fluid in the washer vat —5— for the purpose of increasing the capacity of the cage to approximately the actual working capacity of the washer vat so that the maximum batch of clothes capable of being operated upon at one time may, when thoroughly washed and cleansed, be transferred to the drier cage for drying purposes.

105 As previously stated, the drier vat —25— is of considerably less diameter than its vertical height so that the wet clothes which are packed therein by hand may be brought as closely as practicable to the axis of rotation of the cage for reducing the vibration of said cage when rotated at relatively high 110 speed in case the center of weight of the clothes should be more or less eccentric to said axis.

115 It will also be noted that the bearing post —24— for the shaft —27— and the hub —26— of the cage are extended some distance upwardly from the bottom of the cage into the interior thereof to assist in holding the cage against lateral vibration due to any slight eccentricity of the center of weight of 120

125 130

the clothes in the cage as the latter is rotated.

Furthermore, in case the weight of the clothes within the cage is not evenly distributed around the axis thereof, which would tend to produce more or less lateral vibration of the cage, the downwardly diverging sides or walls of the shell —25" — will assist in feeding the clothes downwardly aided by the weight of the clothes into the larger lower end of the cage by reason of the impact of the clothes with the downwardly and outwardly inclined walls thereby bringing the center of weight of the clothes more nearly around the bearings of the cage and shaft to further reduce the lateral vibration of said cage when the latter is rotated with the clothes therein.

Another advantage in making the cage of greater vertical height than its diameter to obtain the desired capacity of the cage is that the washer and drier mechanisms may be brought into closer or more compact relation and this advantage is further increased by making the washing vat crescent-shaped and nesting the drier vat in the concave side of the washer vat so that both mechanisms may be brought within a circumference having a radius approximately equal to the radius of the convex side of the vat.

A further advantage of this compact relation of the washer and drier mechanism together with the power unit is that the inertia of the entire machine is practically sufficient to prevent the transmission of any vibration incidental to the rotation of the drier cage with the clothes therein to the machine as a whole so that when the latter is placed in any particular position it will remain in that position even though mounted on rollers or casters without perceptible vibratory movement.

I claim:

In a washing machine of the character described, a cylindrical casing, a vat therein having a cylindrical convex side conforming to the curvature of the casing and disposed adjacent thereto and a cylindrical concave side spaced from the opposite side of the casing and there being lobes on each side on the concave side of said vat, a second cylindrical vat in the casing nesting in the concave side of the first named vat, a rotary centrifuge in the second vat, a vertically reciprocating clothes washer in the first named vat including a vertically reciprocable shaft and a clothes washing element thereon projecting at each side of the shaft within the end lobes.

In witness whereof I have hereunto set my hand this 30th day of January, 1928.

PETER E. GELDHOF.
